Primary Examiner — Katrina A Betton*(74) Attorney, Agent, or Firm* — Foley & Lardner LLP(57) **CLAIM**

The ornamental design for automobile adornment, as shown and described.

DESCRIPTION

FIG. 1 is a front elevational view of automobile adornment showing our new design;

FIG. 2 is a rear elevational view thereof;

FIG. 3 is a right side view thereof;

FIG. 4 is a left side view thereof;

FIG. 5 is a top view thereof;

FIG. 6 is a bottom view thereof; and,

FIG. 7 is a front elevational view of our new automobile adornment design applied to an automobile.

The automobile is shown in broken lines for illustrative purposes only and forms no part of the claimed design.
